UNITED STATES PATENT OFFICE.

JOHN HOWARD McELROY, OF CHICAGO, ILLINOIS.

VOTING-MACHINE.

941,802.

Specification of Letters Patent. Patented Nov. 30, 1909.

Application filed June 8, 1899. Serial No. 719,758.

To all whom it may concern:

Be it known that I, JOHN HOWARD McELROY, a resident of Chicago, in the county of Cook and State of Illinois, have invented 5 certain new and useful Improvements in Voting-Machines, of which the following is a specification.

My invention is concerned with certain new and useful improvements in the interlocking mechanism of voting machines, which is the mechanism associated with the individual candidate registering or counting mechanisms to prevent the voter from casting, or attempting to cast, his ballot for 10 more candidates than there are offices to be filled, and my invention is concerned with a simple mechanism of the class described, which is available not only for single-candidate-to-be-elected groups but more especially for multi-candidate-to-be-elected groups.

Referring to the drawings, in which the same letters of reference are used to designate identical parts in all the figures, Figure 25 1 is a plan view with the cover removed, and with the lower portion of the machine in section on the line 1—1 of Fig. 2; Fig. 2 is a vertical section through the machine on the line 2—2 of Fig. 1; Fig. 3 is a vertical 30 section on the line 3—3 of Fig. 1; Fig. 4 is a fragmentary plan view on the line 4—4 of Fig. 2; Figs. 5, 6 and 7 are a plan view, side elevation, and end elevation, respectively, of the ballots holder; Fig. 8 is a section of the same on the line 8—8 of Fig. 5; Figs. 9, 10 and 11 are a side elevation, perspective, and longitudinal section, respectively, of the holder employed for use in connection with the irregular balloting 35 mechanism.

My present voting machine takes the general form of a ballot box, and is of the type of machines where actual tokens or ballots are employed to register each vote 45 cast for each candidate. The box consists of the bottom piece A, the end pieces B, the side pieces C, and the lid D, which may be hinged to the rear side piece C so as to be turned up when the machine is in use, or it 50 may be entirely removed during the election.

The ballots or tokens E I preferably make in the form of disks, which in size and shape may be similar to one of the smaller coins, such as a penny, or the nickel five-cent piece.

If desired, the ballots for each office may be 55 separately marked, but this is an unnecessary refinement. These tokens or ballots E are deposited in the ballot holders F, which are a series of elongated metallic tubes, the tubes for each party being conveniently arranged 60 upon a single slide G, which rests upon the bottom piece A, and when the returns of the election are to be canvassed, the door H in one of the sides C is unlocked and swung down about the hinges J so that the slides G 65 can be withdrawn one at a time and the ballots therein for each individual candidate counted. To facilitate the counting of these ballots without stopping to handle each one, I form the two staggered rows of perforations K in the outer side of the tubes, and between these perforations I form a scale, and the perforations overlap sufficiently so that the height of the disks in each tube can be readily seen, and by comparing the 70 height with the scale, the number of ballots in each tube, and the consequent number of votes cast for that particular candidate with that machine can be readily and speedily ascertained. These tubes are conveniently 75 formed of sheet metal, and may be slipped over or secured to the circular blocks L which are screwed down to the slides G, as shown in Fig. 2. While the tokens before being actually deposited in the tubes are 80 placed in a straight line, as indicated by the position of the apertures T in Fig. 1, for economy of space, I preferably arrange these tubes F in a staggered row, as best shown in Fig. 1. To assist in directing the tokens 85 into their respective tubes, I may form the flanges M projecting from the top of each of the tubes, as shown in Figs. 1 and 2. While I have shown the box as comparatively shallow, and the tubes as capable of 90 accommodating only comparatively a small number of ballots, it will be understood that in practice the tubes will be three or four feet long, so as to be able to accommodate as high as five hundred tokens in each tube, 95 which is the maximum number that would ever be cast for any one candidate, as the machines are designed to accommodate about six hundred voters in a precinct, and one machine should be employed in each precinct.

The controlling mechanism for the ballots or tokens consists of a movable plate N

which is substantially the width of the inside of the machine, and the main body portion is the length of the inside of the machine less the longitudinal distance that it is moved in operating and re-setting the machine. This plate is supported upon ledges or shelves O (see especially Fig. 2), which are secured to the end walls and supported preferably by brackets P. This plate is provided with a number of apertures Q, which are of the width and length to permit the ready passage of a token through them and into the tubes F. In its normal position, however, the apertures Q are so placed as to be out of register with the tokens placed in the machine, so as to prevent their falling into the tubes.

A short distance above the plate N, preferably slightly less than the radius of one of the tokens, is fixed a plate R, which is preferably metallic, and covers the entire interior of the machine, it being conveniently secured in place by being made wider and longer than the inside of the machine, and taking into grooves S formed in the sides and ends of the vertical walls of the machine. This plate R is formed with a series of slots T therein, which, as previously stated, are formed in straight lines representing the parties, and there is one slot for each candidate and tube F, and these slots are slightly longer than the diameter of the token, and slightly wider than its thickness, and bear the relation to the apertures Q in the plate N so that when the tokens are placed in the slots T they will be held substantially vertical, and will rest on the plate N between the apertures Q.

On the plate R are located a number of controlling blocks U, which are secured in channels formed on the plate R by longitudinal strips V which are conveniently bolted or riveted to the upper side of the plate R, but which might be formed integral therewith if desired. These blocks U are of the shape shown in Figs. 1, 2 and 3, and consist of elongated rectangular blocks having the upper portions of their sides and ends beveled off, say at an angle of sixty degrees. To conveniently secure these blocks in their channels, and to prevent their removal, the strips V have secured on their upper sides the strips W, which I preferably form of glass, so that a printed paper strip containing the name of the candidate and the office for which he is running may be placed between the upper side of the strip V and the under side of the strip W, and thus be visible to the person using the machine. These strips W have their sides beveled at an angle corresponding to that at which the sides of the blocks U are beveled, so that the strips W overhang the blocks U and prevent their being lifted up. The strips V and W are also continued at the sides and ends of the

machine, so as to form the ends of the channels, and these ends are likewise beveled so as to prevent the withdrawal of the blocks. In each of these channels is placed a number of blocks preferably corresponding to the number of political parties, and the channel is enough longer than the combined lengths of the blocks so as to make it possible to completely uncover one, and only one, of the slots T in each channel, so that only one token can be placed in a channel at a time. Of course, it will be understood that each channel is devoted to the candidates of the different political parties for the same office.

The general operation of the device will now be readily apparent, as if a token is placed in position for one candidate for each office to be filled, and the voter can put only one token in place, and after the voter has left the machine, the plate N is pulled to the left by means of the handle X which is attached to an extension Y of the plate N, which extension passes through an aperture Z in the end of the machine, the tokens placed in the slots T, which are supported by the plate N while the voter was at the machine are permitted to fall through the apertures Q and into the tubes F, as the movement of the plate N by the judge of the election, or automatically as the voter leaves the booth, serves to bring the apertures Q beneath the slots T.

To provide for the rapid placing of the tokens in the slots T if a straight ticket, or a substantially straight ticket, is to be voted, I provide the following mechanism: To get all of the slots T accessible for the particular party for which the voter desires to cast a substantially straight ballot, I place two rods A' across the machine near to the sides and these rods may be secured in place by a bolt head and a nut on the outside of the box, as shown. Upon these rods slides an adjusting mechanism B' which may conveniently be constructed of the two tubes G' sliding on the rods A', and conducted by the rigid rod D' which may be conveniently screw-threaded into offsets in the tubes C', and by the rod E' which is pivotally mounted at its ends to the tubes C' and extends parallel to the rigid rod D'. This rod or rock-shaft E' is provided with a number of arms F', the inner ends of which are shaped so as to engage with the ends of the blocks U which project above the surface formed by the strips W.

The operation of this device will be readily apparent. Assuming that it is in the position shown in Fig. 1, if the voter desires to vote the straight ticket for the party occupying the first column, he will shove the device B' to the right the length of one block U, when, of course, all the blocks will be carried from over the column

in which he desires to place the tokens. Should he desire to cast a vote for the party occupying the third column, instead of stopping the operation at this point, he will then 5 turn the rock-shaft E' upward and over an angle of about 240°, when the arms F' will be pointed in the opposite direction, and ready to engage the opposite ends of the blocks. The device B' is then slid until the 10 arms F' engage the ends of the blocks U which are over the column he desires to vote for, and the device B' is then shoved to the left for the length of one block U, thus uncovering the apertures T of the party for 15 which he desires to vote. To further assist the rapid placing of the tokens E, I preferably provide a carrier G', shown in Figs. 5 to 8, the object of which is to hold the complete set of tokens for all the offices to be 20 filled in position so that they can be instantly dropped into the slots T. A plurality of the carriers G' is provided, and the tokens are in the hands of some election officials, who keep the carriers filled with the 25 necessary tokens, so that a voter before entering the booth in which the machine is placed is provided with a carrier containing all the necessary tokens. After the blocks U have been manipulated by means of the 30 device B', as previously set out, the carrier G' is placed in the appropriate pair of the recesses H' which are formed in the parts J' which are secured above the continuation of the strips W and next to the side walls C. 35 The width of these notches H' is just sufficient to accommodate the ends of the carrier, which are placed across the machine so as to place the lower end of each token just above the slots T. The carrier is then manipulated 40 so as to drop the tokens into the slots T, and the carrier is then removed. If any candidate is to be scratched, the token in his slot is lifted out, and the slide U covering the slot for the candidate for whom it is desired 45 to vote is moved so as to cover the slot from which the token was taken and to uncover the slot in which the token is to be placed. After the tokens have all been adjusted, the work of the voter is completed, 50 and he can leave the booth.

The specific details of the construction of the carrier G' will now be described. It is in the form of a clamp, consisting of the jaw K' which may be composed of a comparatively thin sheet of metal; having a handle L' formed thereby extending a portion of the sheet K upward and turning over the edges of the upwardly projecting portion, as shown at M'. The ends of the clamping 55 member K' are preferably turned at right angles to form the ends N', which, of course, are a width to fit into the notches or recesses H'. I preferably also make the end portions N' wider than the body portion K' 60 so as to turn up the lower portion O' thereof

at right angles, so as to furnish a little greater bearing support for the carrier. The other clamping member may consist of a tubular body portion P' which is secured in position by the rod or bolt Q' passing therethrough and through apertures in the ends N', outside of which said rod is headed or riveted so as to secure it in position. The body portion P' is provided with a handle R' opposite the handle L' of the other 70 clamping member, and an expanding coiled spring S' is secured between these handles and tends to keep them apart. The jaws T' of this member are of the shape best shown in Fig. 8, where it will be seen that they are 75 formed integral with the tubular body portion P', and are of a shape to clamp the token against the opposing plate, which might also be slotted if desired. The inner sides of the jaws T' are provided with the 80 grooves U' which are of a width and depth to securely hold the token in the position shown in Fig. 8. When the carrier is placed in the depositing position, each of the tokens E will be above a slot T, and when the handles M' and R' are brought together by the 85 movement of the handle R' against the resistance of the spring S', the tokens will be released, and will fall into the slots T, as 90 previously explained.

In some States, there are different classes of voters, depending upon the amount of suffrage that is extended to them. For instance, in the State of Illinois, the women of legal age are permitted to vote for all the 100 educational officials, and in the State elections, they have the privilege of voting for the three trustees of the State University which are elected at the time of the congressional elections. This necessitates making some provision whereby voters of a limited franchise can be provided for, and in the present machine I have illustrated a construction in which the three ballots for the trustees of the State University can be cast 105 by a voter having that limited franchise without the possibility of casting any for some other office to which they are not entitled to vote. This I accomplish by dividing the plate N into two parts, and so connecting these parts that when a voter having a full franchise has deposited his ballot, the entire plate N will be moved, depositing in the machine all the tokens which can be placed therein. When a voter having a limited franchise votes, only the portion of the plate N pertaining to the receptacles for that office and which portion I have lettered V', will be moved, and, consequently, if the tokens are placed elsewhere than in the slots 110 in which they should be placed, they will not be cast when the voter leaves the machine. Referring especially to Fig. 4, where I have shown the plate V' as in its operated position, it will be seen that it is flush with 115 120 125 130

the plate N, which is, on account of the position of this plate V', virtually separated into two parts, which, however, are connected by two or more cross pieces J' shown only 5 in Fig. 2, and connect the two parts of the plate N passing beneath the plate V'. The plate V' has the general shape shown in Fig. 4, and is provided with an extension W' and a handle X' similar to the main handle 10 X of the plate N. The rear portion of this plate V' has two offset portions as at Y', forming shoulders that coöperate with the complementary shoulders Z' on the plate N, so that when the plate N is drawn forward, 15 the shoulders Z' coöperating with the shoulders Y' will also carry the plate V' forward, but when the plate V' is carried forward, it does not move the plate N. Thus, it will be seen that if the voter of limited franchise 20 should place the three tokens furnished in the slots for some officials of more importance, the election officials by moving only the handle X' would not permit any improperly placed tokens to be cast into the 25 machine.

As is well known, groups of officials are sometimes elected, and such groups are known as multi-candidate groups. As they are ordinarily voted for, each party nominates one candidate for each place, and as 30 in the case of the trustees for the State University, just considered, each party nominates three candidates, but the voter is at liberty to cast one of his votes for the candidate of the Republican party, another for 35 a candidate of the Democratic party, and perhaps a third for a candidate of the Prohibition party. In such case, it might occur that the apertures T in which he desired to 40 place the ballots are all in the same longitudinal channel, so that if the ordinary construction were employed for these grouped candidates, it would be impossible for the voter to cast his ballot for the candidates 45 desired, because he could not open the three slots in the same channel. To overcome this difficulty, in multi-candidate groups, I provide connections between the three channels at one or both ends, so that it is possible to 50 get one channel completely filled with the blocks U, while another channel has the customary number of blocks in it, while the third channel has one less than the customary number of blocks in it, so that one token 55 could be placed in the second channel and two in the third channel. Or the blocks can be so adjusted that the first and second channels will be entirely filled with the blocks, while there will be three vacant spaces in 60 the third channel. It will be readily apparent that this same system of moving the ballot controlling blocks from one channel to the other for multi-candidate voting may be readily applied to the equivalent construction in which there are only as many 65

blocks in each group as the ballot counting mechanisms that can be actuated in the group by a single voter.

As shown at the right hand side of the machine, there is space for a set of blocks 70 beneath which there are no holders. These blocks are used principally for re-setting purposes, as will be subsequently explained. The strips V and W extend between the blocks of this extreme right hand end portion, as shown in the upper part of Fig. 1, 75 except between the three blocks of the multi-candidate group, where the strips V and W are cut out and their place is taken by two extra blocks. At the opposite or left hand 80 end of the machine, I may form a similar space, as shown at A², and fill it with five blocks U, three of which correspond to the positions of the blocks in the channel, and two of which serve as fillers to take up the 85 space. In the complete system, there are blocks enough to fill up the complete channel space and the end space A², except for three blocks. It will be seen that these blocks cannot be lifted out of position on account of the overhanging portions of the strips W or their continuations overhanging the beveled portions of the blocks. It will 90 also be seen that by means of shifting these blocks across the ends, as may be necessary, any three slots T in the entire multi-candidate group can be uncovered. When it is desired to vote for two or more candidates in the same row of a multicandidate group, 95 some of the interlocking blocks N in the connecting end of the channel must be moved into the row or rows in which no candidates are to be voted for. The space in the connecting channel thus secured is filled by moving in the blocks from the row or rows 100 in which more than one candidate is to be voted for. By a little manipulation, it will be apparent that any necessary arrangement of blocks within the capacity of the machine can readily be made. 110

It is desirable to re-set the machine after each person has voted so that the next voter entering the booth cannot by an inspection of the blocks see how the last voter has cast his ballot. It is primarily for this purpose that the right hand end row of blocks U is provided. Just beneath this row of blocks is a series of slots B², which are about half the width of the block, and exactly of the length of a block. The plate N has rigidly fastened therein and projecting upwardly therefrom the teeth C², which are of the shape shown in Fig. 2. These teeth C² project upwardly through the slots B² and when the plate N is in its normal position are directly behind the right hand end blocks U. As the plate N is moved to cast the ballots, these teeth C² taking against the ends of the blocks U at the right hand end of the machine will move them and, consequently, those to the left of 125 130

them, one space to the left, so that the voter entering the machine will find all of the blocks U at the left hand side of the machine, and all the slots T covered so that he 5 cannot tell how the voter immediately preceding him has voted. In connection with the multi-candidate group, a slight modification of this structure is necessary, as it may sometimes occur, when a person is voting 10 a scratched ticket, that he may cast ballots for two men in the same horizontal row, in which case one of the other horizontal rows would be filled with blocks so that as the machine was re-set, it would be impossible to 15 move the block U at the right hand end to the left in resetting, inasmuch as the channel is entirely filled. Consequently, it becomes necessary in connection with this 20 multi-candidate group to have the teeth C² arranged with yielding connections, so that if any channel is full, the machine will not be broken in an endeavor to re-set it. For this purpose, I place the teeth C² of the 25 multi-candidate group in special slides D², which slides are placed in channels E² formed in the plate V', or they will be in the plate N if the multi-candidate group did not at the same time belong to the limited franchise group, as in the present case. The 30 slide D² has secured to its upper side a cross piece F², to which are secured two long helically coiled springs G² which are also secured to the plate V'. A pin or other cross piece H² passing through the teeth C² of the 35 multi-candidate group beneath the slots J² in the right hand supporting plate O serves to hold the plates D² in position against any possible tendency of the spring to tilt them or otherwise disarrange them. When the 40 channel of any of the multi-candidate groups is filled with blocks, and the plate V' is moved forward either directly or by means of the movement of the plate N, the plate D² of that particular channel remains stationary, as illustrated in the central one in 45 Fig. 4, and the expansion of the springs G² permits this. The strength of the springs G² is sufficient to overcome the sliding resistance of the blocks, and thus re-set them, if the blocks are so positioned as to leave a 50 vacant space in the channels.

The right hand set of tubes and slots is provided for irregular balloting, and this I 55 preferably accomplish by having the token in the form of a holder, such as shown in Figs. 9 to 11, into which a piece of paper having the name of the candidate written thereon can be inserted, and the holder inserted in the machine just the same as a token. I 60 preferably make the apertures T for the irregular balloting of twice the width of the ordinary apertures, so as to enable me to make the holder of greater thickness. These holders may be of any desired form, 65 but I preferably make them of the shape

shown in Fig. 9, where it will be seen that the lower half of the holder K² is dish-shaped, while the upper half is mostly cut away, except a tongue L², which presses down into the central portion of the holder and serves to hold the folded ballot which is placed therein securely in the holder and prevent its being displaced. Of course, I might make these holders somewhat like a pill box, and of two separate parts, but the 70 structure shown consisting of a single metallic sheet metal piece is preferable as there is no possibility of the parts becoming separated.

While I have shown the various features 80 of my invention as applied to a token receiving voting machine, it will be apparent that some features thereof might be applied to the more common type of machines in which wheel registers operated or controlled 85 by candidate keys are employed. For instance, it will be apparent that the interlocking block system for the multi-candidate groups might be applied to the keys for such a wheel register instead of to the tokens. 90 Similarly the method of controlling the limited franchise voters by only arranging the machine to operate such ballot candidate mechanisms as their franchise entitles them to operate might also be applied to a wheel 95 register voting machine. Consequently, when I employ the term "register mechanisms" or "ballot counting mechanisms" etc., I do not desire to be understood as limiting myself to any one form of mechanism. 100

While I have shown my invention as embodied in a form which I at present consider best adapted to carry out its purposes, it will be understood that it is capable of modifications, and that I do not desire to be 105 limited in the interpretation of the following claims by the language thereof, but only as may be necessitated by the state of the prior art.

While I have shown and described the 110 general mechanism connected with the above mentioned machine, irrespective of the interlocking mechanism employed, I do not herein claim the same, the present application being limited to the interlocking mechanism, 115 but reserve the subject-matter of the same for a divisional application.

Having now described my invention, what I claim as new, and desire to secure by Letters Patent of the United States, is:

1: In a machine of the class described, the combination of a series of voting mechanisms arranged in party columns and office rows, with plural series of interlocking blocks sliding freely in office rows and serving to prevent the actuation of said voting mechanisms for more than one candidate in a row, and a member contacting directly therewith for moving all of said blocks simultaneously, if desired, to render operable 125 130

all the voting mechanisms in any one party column desired, said member being movable transversely of the machine so that it may engage any party column.

5 2. In a machine of the class described, the combination of a series of voting mechanisms arranged in party columns and office rows, with plural series of interlocking blocks sliding freely in the office rows and serving to prevent the actuation of said voting mechanisms for more than one candidate in an office row, and a member contacting directly therewith for moving all of said blocks simultaneously, if desired, in either 10 direction to render operable all the voting mechanisms in any one party column desired, said member being movable transversely of the machine so that it may engage any party column.

15 3. In a machine of the class described, the combination of a series of voting mechanisms arranged in party columns and office rows, with plural series of interlocking blocks sliding in said office rows and serving 20 to prevent the actuation of said voting mechanisms for more than one candidate in a row, and mechanism for moving all of said blocks simultaneously, if desired, to render operable all the voting mechanisms in any 25 one party column desired, said mechanism comprising a bar extending across the machine, together with ways upon which said bar slides, and fingers on said bar adapted to engage the ends of the blocks.

30 4. In a machine of the class described, the combination of a series of voting mechanisms arranged in party columns and office rows, with plural series of interlocking blocks sliding in said office rows and serving 35 to prevent the actuation of said voting mechanisms for more than one candidate in a row, and mechanism for moving all of said blocks simultaneously, if desired, to render operable all the voting mechanisms in any 40 one party column desired, said mechanism comprising a bar extending across the machine, together with ways upon which said bar slides, and fingers on said bar which 45 can be turned to point in either direction and adapted to engage the ends of the blocks.

50 5. In a machine of the class described, the combination of a multi-candidate group of voting mechanisms arranged in intersecting party columns and office rows, with a series 55 of interlocking members movable along the office rows to limit the number of votes to be cast in the group, and a series of channels in which said members are confined, said channels having space for a limited number 60 of said members and connected so as to permit the passage of the members from one channel to another, but without any possibility of removal therefrom.

65 6. In a machine of the class described, the combination of a multi-candidate group of

voting mechanisms arranged in intersecting party columns and office rows, with the series of interlocking blocks U movable along the office rows to limit the number of votes to be cast in the group, the series of channels in which said blocks slide but from which they cannot be withdrawn, and the cross channels connecting the ends of said channels, and in which said blocks can be moved to transfer them from one channel to another but without removal, the entire channel space being arranged to accommodate a limited number of blocks, substantially as shown and described. 70

7. In a machine of the class described, the combination of a multi-candidate group of voting mechanisms arranged in party columns and office rows, with a series of interlocking blocks movable along the office rows to limit the number of votes to be cast in the group, a series of channels in which said blocks are confined, said channels having space for a limited number of said blocks and connected so as to permit their passage from one channel to another without the possibility of removal therefrom, and mechanism for moving said blocks in each office row to prevent a subsequent voter from seeing how the prior voter has voted, said mechanism being spring actuated so as to permit it to yield when necessary. 80

8. In a machine of the class described, the combination of a multi-candidate group of voting mechanisms arranged in party columns and office rows, with a series of interlocking blocks movable along the office rows to limit the number of votes to be cast in the group, a series of channels in which said blocks are confined, said channels having space for a limited number of said blocks 100 and connected so as to permit their passage from one channel to another without the possibility of removal therefrom, and mechanism for moving said blocks to re-set them comprising the teeth C² mounted in the sliding blocks D² arranged to slide longitudinally in the re-setting plate V', and connected thereto by the coiled springs G², substantially as described. 105

9. In a voting machine, the combination with a plurality of individual voting mechanisms arranged in party columns and office rows, of controlling mechanism for regulating the operation of the voting mechanisms comprising a plurality of parallel channels 115 each having a plurality of voting mechanisms associated therewith representing a competing set of candidates for the same office, a plurality of blocks movable in said channels whose final positions therein control the operation of the voting mechanisms, and a transverse connection between said channels through which the blocks may be moved from one channel to another to group them as may be necessary for actuating two 120

or more voting mechanisms associated with a single channel.

10. In a voting machine, means provided with a plurality of communicating parallel channels, vote limiting means arranged in said channels whereby the limiting means in one channel may be shifted to another channel.

11. In a voting machine, a vote limiting system provided with a plurality of communicating parallel channels and vote limiting means arranged in said channels so that

the limiting means may be shifted from one channel to another but cannot be removed from the system.

12. An interlock structure comprising a longitudinal race way, separable interlock mechanisms therein and means permitting lateral displacement of some of said mechanisms.

JOHN HOWARD McELROY.
